(74) Attorney, Agent, or Firm — Suzanne Kikel, Patent Agent

(57) **CLAIM**

The ornamental design for a curved ironing board, as shown and described.

DESCRIPTION

FIG. 1 is a front perspective view of a curved ironing board, showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right elevational view thereof; and,

FIG. 7 is a left elevational view thereof.

The broken lines shown in the figures are for the purpose of illustrating portions of the curved ironing board and form no part of the claimed design.

1 Claim, 7 Drawing Sheets
